UNITED STATES PATENT OFFICE.

ALFRED S. ADAMS, WILLIS BURTON ADAMS, AND PAUL S. MOYER, OF CHICAGO, ILLINOIS.

DESIGN FOR A CANDY JAR.

Application filed November 29, 1926. Serial No. 19,877. Term of patent 14 years.

To all whom it may concern:

Be it known that we, ALFRED S. ADAMS, WILLIS BURTON ADAMS, and PAUL S. MOYER, citizens of the United States, residing at Chicago, in the county of Cook and State of Illinois, have invented a new, original, and ornamental Design for Candy Jars, of which the following is a specification, reference being had to the accompanying drawing, forming part thereof.

In these drawings,

We claim:

The ornamental design for a candy jar as shown.
